UNITED STATES PATENT OFFICE.

WALTER M. CROSS, OF KANSAS CITY, MISSOURI.

TURBINE.

Application filed August 20, 1924. Serial No. 733,082.

This invention relates to improvements in turbines and refers more particularly to a reinforcement shell into which the turbine is placed in order to withstand high pressures at which the turbine is operated.

Among the salient objects of the invention are, to provide a turbine construction adapted to be used with high pressures and temperatures, such as pressures in excess of 800 to 1,000 pounds per square inch; to provide a construction which eliminates the difficulty of leakage from expansion and contraction and which leakage would be increased under the high pressures at which a turbine of this character is operated; to provide a construction which permits the utilization of high pressures without the attendant dangers due to the enclosing of the entire construction in a heavy reinforced forged steel casing, and, in general, to provide a construction of the character referred to.

Fig. 1 is a sectional side view showing the turbine construction diagrammatically with parts of the shaft bearings or journals broken away.

Fig. 2 is a view taken along the line 2—2 in Fig. 1.

Fig. 3 is a right-hand end view of the reinforcement shell with a journal bearing and turbine removed.

Fig. 4 is a view of the internal casing divided to show the turbine rotor.

In the drawings, the turbine shown is of the Parsons type, and for simplicity the details of the construction have been shown only diagrammatically. The forged reinforcement shell 1 has two end plates or journal plates 2 and 3 which support the rotor shaft 4. On the shaft is mounted a drum 5, upon the periphery of which are positioned the rotating vanes 6. Between these rotating vanes are stationary vanes 7 which are mounted within the separate halves of the interior casing 8. Normally the casing 8 is constructed sufficiently strong to withstand steam pressure at which the turbine is operated. In the present construction, however, it is unnecessary, due to the fact that it is enclosed within the reinforcement shell and therefore this inner casing need only have sufficient strength to properly support the stationary vanes.

The internal casing is formed in separate stages of operation, the steam passing from the smaller high pressure stage progressively to the larger low pressure stages. In the

drawings, but three stages have been shown, but any one may be utilized to obtain the most efficient operation and in order to extract the greater amount of work from the power medium.

To assemble the turbine, the rotor, consisting of the drum 5 upon which the rotating vanes are mounted and shaft 4, is inserted within the two halves of the interior casing 8 in the manner shown in Fig. 1, so that the stationary vanes of the casing alternate with the rotating vanes of the rotor. This casing is then slid into the reinforcement shell and may be wedged into position either by slightly tapering the separate shoulders of the different stages to fit tightly into the tapered interior walls of the shell or the casing may be keyed in the shell by means of a key shown at 9 to prevent the rotation of the casing in the shell. The journal plates 2 and 3 are then bolted onto the outside shell and properly gasketed in order to form a pressure-tight enclosure for the turbine casing. The journal plate 2 is equipped with a high pressure channel 10 to which is connected the high pressure steam line 11 and the journal plate 3 with the low pressure exhaust channel 12 to which is connected the low pressure line 13. The steam is introduced at high pressure through the line 11 from any convenient source, preferably the pressures in excess of 800 to 1,000 pounds per square inch. This high pressure steam is directed by the initial stationary vane on to the first high pressure rotor from which it is ricocheted from the successive stationary and rotating vanes from the high pressure through the succeeding low pressure stages in a manner well known to those versed in the art.

As suggested heretofore, the particular type of turbine construction forms no part of the present invention, as any turbine may be used which can efficiently be operated at high pressures mentioned. As described, the invention lies broadly in the positioning of the turbine casing in a high pressure reinforcement shell which is preferably of heavy forged steel construction such as that shown in Fig. 3,—the shell containing the casing being formed in a single unit of uniform texture and strength which is built to withstand the excessive pressures and temperatures to which it is subjected. To disassemble the turbine in case repairs are necessary, the end journals are removed, the casing

jacked from the reenforcement shell, the interior casing divided and repairs made in the usual manner.

Heretofore, difficulties have been experienced in maintaining high pressure turbine casings tight, particularly where the separate halves of the casing are fitted together due to the uneven heating of the high and low pressure stages. The construction shown utilizing the reenforcement shell eliminates these difficulties as the whole turbine assembly is positioned within the unitary pressure-tight reenforcement element and leakage due to high pressure eliminated by the use of heavily gasketed journal plates which are easily kept tight due to the uniform heating in the restricted sections to which the pressure joints are limited.

I claim as my invention:

1. A steam turbine consisting of a divided casing, a rotor positioned therein, a second supplementary pressure-tight reenforcement

shell surrounding the complete turbine assembly and fabricated as a single unitary shell having end enclosures, bearings in the end enclosures adapted to carry the rotor, inlet and exhaust ports in the reenforcement shell for supplying and exhausting the power medium.

2. A steam turbine, consisting of a divided casing, a rotor positioned therein, a second supplementary pressure-tight reenforcement shell of substantially greater strength than the inner shell and adapted to withstand pressure in excess of one thousand pounds per square inch, surrounding the complete turbine assembly and fabricated as a unitary forged steel shell, removable end plates for the shell carrying the rotor bearings, inlet and exhaust ports in the shell for supplying and exhausting a power medium.

WALTER M. CROSS.
